UNITED STATES PATENT OFFICE.

JULIUS B. MELTZ, OF EVERETT, MASSACHUSETTS, ASSIGNOR TO LOUIS I. BECKWITH, OF BOSTON, MASSACHUSETTS.

DESIGN FOR A LUGGAGE-CARRIER OR SIMILAR ARTICLE.

53,970.

Specification for Design.

Patented Oct. 14, 1919.

Application filed April 23, 1919. Serial No. 292,177. Term of patent 14 years.

To all whom it may concern:

Be it known that I, JULIUS B. MELTZ, a citizen of the United States of America, residing at Everett, in the county of Middlesex and Commonwealth of Massachusetts, have invented a new, original, and ornamental Design for a Luggage-Carrier or Similar Article, of which the following is a specification, reference being had to the accompanying drawing, forming a part thereof.

In said drawing Figure 1 is a plan view of a luggage carrier showing my new design; and

Fig. 2 is a section on the line 2—2 of Fig. 1.
I claim:

The ornamental design for a luggage carrier or similar article, substantially as shown.

Signed by me at Boston, in the county of Suffolk and Commonwealth of Massachusetts, this 15th day of April, 1919.

JULIUS B. MELTZ.
